UNITED STATES PATENT OFFICE

ROBERT T. HAZELTON, OF CINCINNATI, OHIO, ASSIGNOR TO THE CINCINNATI SHAPER COMPANY, OF CINCINNATI, OHIO, A CORPORATION OF OHIO

CLAPPER BOX

Application filed July 8, 1929. Serial No. 376,679.

My invention relates to clapper boxes as employed with traversing machines such as shapers and planers, in which the boxes are employed to retain a tool in working position 5 against a piece of work while traversing across it in one direction, and to permit the tool to pass idly over the surface of the work while traversing in the other direction.

Various expedients have been adopted in 10 the structure of planers and shapers to the end of assuring a firm seat fully protected against strains in all directions for the clappers that hold the tools in the boxes. In most of these the clapper is provided with a 15 seat between side bars of the box that supports it, and in addition, some kind of seat which will take up vertical thrust.

It is the object of my invention to provide 20 for a seating method for clappers which will be easy to arrange, strong in its action, and makes it unnecessary to machine either the box or the clapper in order to provide for the several seats. It is a further object to 25 provide for a simple method of pivoting the clapper box on the saddle.

I accomplish my object by that certain construction and arrangement of parts to be hereinafter more specifically pointed out and claimed.

30 In the drawing:—

Figure 1 is a side elevation partly broken away of the clapper and part of the box.

Figure 2 is a front elevation of the same.

Figure 3 is an assembly view showing the 35 saddle and clapper box mounting.

Figure 4 is a bottom plan view illustrating the seating structure of the clapper in the box.

40 The clapper box is shown at 1, with the clapper 2, said box having a post 3 in which the tool 4 is held in the usual manner. The box has the usual side rails 5, 5, and the clapper is swung on the pivot bolt 6, so that it 45 lies, when in working position, between the side rails.

It is not necessary to provide for a careful fit with machined surfaces of great accuracy between the side rails and the sides of the 50 clapper, nor is it necessary to provide ridges

in the box and shoulders on the clapper for engaging them.

Instead of this I provide, in the two lower corners of the box, for the mounting of two hardened bushings 6a, 6a, said bushings having 55 conical recesses in them facing outwardly.

Formed on the two lower corners of the clapper are a pair of heavy lugs or posts 7, 7, which project inwardly therefrom and are ground to a careful fit within the bushings, 60 the ends which fit into the bushings being indicated at 8.

Other ways of providing for the portions 65 on the clapper box which fit within the bushings may be provided, and also the bushings themselves, which have the advantage of being replaceable, could be eliminated and the conical cavities bored and ground within the saddle.

It will be noted that in use when the tool 70 is being employed in cutting, the clapper box will have two conical seats which will provide for strains on the tool in all directions, and that upon the return stroke of the clapper box or of the work (in planers) the box can 75 swing easily out of the seated position so that the tool will drag freely over the work.

I find that the seating arrangement so provided is very effective, which would not be the case in a single recess, and it has the advantage of being both repairable and replaceable, which is not the case with other seating arrangements with which I am familiar.

The clapper box, as is normal practice, is 85 pivoted to the saddle 9 so that it can be swung on a horizontal pivot. The slotted head 10 of the clapper box is of usual structure. The novel arrangement is the mode of pivoting the box. To this end a conical post 11 is 90 formed on the center of the lower end of the back of the box, which post is developed at its end into a threaded cylindrical portion 12 to receive the nut 13. A conical recess 14 is formed in the saddle. The post and recess 95 may, however, be cylindrical.

When the box is mounted the post is seated in the recess and the nut turned down to draw the box snugly into place, although not so tightly that it cannot be swung around. 100

This structure is simple and at the same time, strong and sturdy.

Having thus described my invention, what I claim as new and desire to secure by Letters Patent, is:—

1. In a clapper structure, the combination of a clapper box, a clapper, means for pivoting the clapper to the clapper box, said clapper and box being characterized by a pair of 10 conical recesses and coacting conical projections adjacent the lower end thereof and interspaced in a direction transverse to the axis of said clapper and box, said conical projections being of sufficient length to hold 15 said clapper positively a substantial distance away from said clapper box, said conical projections and recesses forming the sole seating means for said clapper with respect to said clapper box.
2. In a clapper structure, the combination of a clapper box, a clapper, means for pivoting the clapper to the clapper box, said clapper and box being characterized by a pair of 20 conical recesses and coacting conical projections adjacent the lower end thereof and interspaced in a direction transverse to the axis of said clapper and box, said conical projections being of sufficient length to hold 25 said clapper positively a substantial distance away from said clapper box, said conical projections and recesses forming the sole seating means for said clapper with respect to said clapper box, said clapper bearing a 30 tool holding means located substantially on the axis of said clapper and substantially 35 above a line drawn through the centers of said conical projections.
3. In a clapper structure, the combination of a clapper box, a clapper, means for pivoting 40 said clapper to said box substantially at the upper end of said clapper, said box being wider than said clapper and characterized by at least a pair of horizontally 45 interspaced conical recesses, said clapper having a pair of conical projections adjacent the lower end thereof extending toward said clapper box and interspaced to coact with 50 said depressions, said projections being of sufficient length to maintain said clapper a substantial distance away from said clapper box, whereby said structure becomes self 55 compensating for wear, the bodies of said projections extending substantially beyond the lines of the edges of the body of said clapper.
4. In a clapper structure, the combination of a clapper box, a clapper, means for pivoting 60 said clapper to said box substantially at the upper end of said clapper, said box being wider than said clapper, and said clapper and box being characterized by at least a pair of horizontally 65 interspaced conical recesses and coacting conical projections adjacent the lower end thereof, said projections being of sufficient length to maintain said

clapper a substantial distance away from said clapper box, whereby said structure becomes self compensating for wear, the pair of said members located on said clapper extending substantially beyond the lines of the 70 edges of the body of said clapper, and a tool post located on said clapper substantially upon the axis thereof.

5. In a clapper structure, the combination of a clapper box, a clapper, means for pivoting said clapper to said box substantially at the upper end of said clapper, said box being wider than said clapper, and said clapper and box being characterized by at least a pair of horizontally 75 interspaced conical recesses and coacting conical projections adjacent the lower end thereof, said projections being of sufficient length to maintain said clapper a substantial distance away from said clapper box, whereby said structure becomes self-compensating for wear, the pair of said members located on said clapper extending substantially beyond the lines of the 80 edges of the body of said clapper, and a tool post located on said clapper substantially upon the axis thereof, the center of said tool post being located substantially above a line drawn between the centers of said pair of members.

6. In a clapper structure, the combination of a clapper box, a clapper, means for pivoting the clapper adjacent its upper end to the clapper box, seating means for the clapper with respect to said box comprising solely a pair of conical depressions widely 90 interspaced, and a pair of co-operating conical projections to engage in said recesses, said conical projections and recesses located respectively on said clapper and box, said projections being of sufficient length to maintain 95 said clapper a substantial distance away from said clapper box, whereby said seating means is self-compensating for wear, and tool-holding means located on said clapper intermediate its upper end and said projections.
